UNITED STATES PATENT OFFICE.

CHRISTIAN RASMUS HANSON, OF SAVANNA, ILLINOIS.

BARBER-POLE.

SPECIFICATION forming part of Letters Patent No. 661,979, dated November 20, 1900.

Application filed August 17, 1900. Serial No. 27,192. (No model.)

To all whom it may concern:

Be it known that I, CHRISTIAN RASMUS HANSON, a citizen of the United States, residing at Savanna, in the county of Carroll and 5 State of Illinois, have invented a new and useful Barber-Pole, of which the following is a specification.

This invention relates to an advertising device, and pertains more particularly to a 10 barber-pole; and the object in view is to provide simple and effective means for rotating and illuminating a pole of the character set forth, so that it will be rendered particularly attractive both during daylight and at night 15 and whereby pleasing designs may be presented and a unique operation produced which will have the desired result of demanding and enticing the attention of persons passing the same, as well as clearly give the 20 location in darkness of the business which it represents.

The invention consists in the construction and arrangement of the several parts, which will be more fully hereinafter described and 25 claimed.

In the drawings, Figure 1 is an elevation of 30 a barber-pole embodying the features of the invention. Fig. 2 is a transverse vertical section of the upper portion of the improved 35 device. Fig. 3 is a horizontal section taken through an intermediate plane thereof.

Similar numerals of reference are employed 40 to indicate corresponding parts in the several views.

The numeral 1 designates a base, which in 45 the present instance is cubical, but may be varied in contour at will and embellished with any suitable applied ornamentation. A pedestal or upright 2 rises from the base and 50 may also be shaped and provided with surface ornamentation, as desired, the upper or top portion of the said pedestal or upright being flat, as at 3, and substantially square to form a stable support. In a suitable seat 55 on this flat top portion of the pedestal the lower end of a glass cylinder 4 is fixed, the upper end of the said cylinder being surmounted by a cap 5, similar in shape to the said flat top, and tied or connected to the 60 latter by four rods 6, preferably formed of brass and having spherical knobs 7 on their upper ends. The surface contour of these

rods may also be varied, as well as the terminal knobs thereof, and the length of the same will depend on the length of the parts between the flat top 3 and the cap 5, and from the center of the latter rises or extends a tubular section 8, on the upper end of which is applied what may be termed a "capital" 9, having a bore 10 therethrough, and gives support to a substantially spherical freely-rotatable propeller 11, having outstanding segmental wings 12 for contact with currents of air. This propeller may also be varied in shape and general construction, and it is proposed to suitably ornament the surface of the capital and section below the same, as well as the propeller itself, in consonance with the design that may be present in the entire device. The propeller has a depending spindle 13 secured thereto, which extends downwardly through the capital and into the section 8 a suitable distance and has a horizontally-disposed friction-disk 14 on the lower end, which rotates therewith. As shown, this disk 15 is sleeved on the spindle and is free to move vertically to compensate for the inward pressure on the propeller, which is provided with an inner socket 15 to fit over the upper extremity of the capital 9 to produce a regular rotative movement thereof and true the 20 spindle in its rotation. The lower end of the spindle is reduced and stepped in a cross-arm 16, diametrically positioned in a ring-frame 17, secured to the interior lower portion of the section 8 and against the wall of a circular opening 18 in the center of the cap 5, the said opening 18 providing means of communication between the section and the cylinder below. The disk 14 normally bears 25 on a vertically-disposed friction-disk 19 on the inner extremity of a short counter-shaft 20, having bearing at opposite ends, respectively, in the ring-frame and the cross-arm thereof. On the outer extremity of the shaft 25 is a pinion 21, which meshes with an annular toothed rim 22, secured to the upper end of an inside normally-transparent cylinder 23, with a lower closed end. Within the cylinder 23 a spider 24 is fixed, and extending centrally therethrough and through the cylinder is a spindle 25, which provides the 30 axis of rotation for said latter cylinder and bearing at opposite ends, respectively, in the

center of the flat top 3 and the under central portion of the arm 16. Resting on the ring-frame 17 is a circular incandescent electric light 26, having suitable feeding connections, 5 and above the same, on the bottom of the capital disposed thereover, is a reflecting plate or surface 27 to throw the light or light-rays downwardly into the cylinders 4 and 23. The cylinder 23, as before stated, is normally 10 transparent; but a very attractive effect is produced by applying spiral stripes 28 there-around on the exterior, which will render the said cylinder translucent, the light showing up the colors of the stripes, preferably red and white, in alternation, and this effect, combined with the rotative action of the cylinder 23 and the reflected light on the exterior thereof within the cylinder 4, will present a very beautiful appearance at night. During 15 daylight it is proposed to cut out the light, and at all times the cylinder 23 will be shielded by the cylinder 4. Many various light effects will be used, and it is proposed to place the lighting device at any point and also to 20 use other motive means, the form set forth being simple and demonstrating one practical adaptation, and as the use of a motor at the present time is within the purview of any invention to which such a device is applicable 25 30 it is also proposed at times to substitute either a spring or an electric motor. The cylinder 23 is the salient feature of the invention when combined with the inclosing cylinder 4, and instead of making said cylinder 35 40 hollow or tubular a suitable length of barber-pole of ordinary solid form may be substituted and arranged to revolve, the same effect being produced by exterior reflection thereon by the light within the cylinder 4 and producing an attractive display through the latter.

In the operation of the simple form of automatic motor shown it is obvious that when the propeller 11 is rotated by the wind or 45 currents of air the cylinder 23 will be correspondingly actuated through the medium of the intermediate mechanism set forth. The several parts are of a durable nature, and though the preferred arrangement has been 50 shown and described it is obvious, aside from the substitutions already noted, that other changes in the form, proportions, size, and minor details may be resorted to without departing from the principle of the invention.

55 Having thus described the invention, what is claimed as new is—

1. A barber-pole having a rotatable member, a fixed transparent cylinder inclosing said

member, and an exteriorly-exposed wind-actuated device for operating the said rotatable member. 60

2. A barber-pole having a rotatable member with a surface design thereon, a stationary transparent cylinder inclosing said member, means engaging the upper portion of the 65 member for rotating the same, and means for illuminating both the member and the interior of the cylinder which is entirely independent of the means for rotating said member.

3. A barber-pole comprising two tubular 70 members, the outer one being fixed and the inner one rotatable and exposed through said outer member, the inner member being operated by mechanism from above the upper end of the same, and lighting means above 75 the plane of both members and operating to illuminate the interior of the inner member.

4. A barber-pole having a rotatable member, a fixed transparent cylinder inclosing said member, means for illuminating the said 80 parts, and an exteriorly-exposed wind-actuated device for operating the said rotatable member.

5. A barber-pole having a base and a pedestal with a flat top, a transparent cylinder 85 stationarily mounted on the said top, a stationary cap on the upper end of the cylinder, vertical rods for connecting the flat top and cap, a capital supported above the cap and having an opening extending therethrough, a 90 striped rotatable member located within the cylinder and having a closed bottom and an open top, mechanism mounted on and extending through the capital and the cap and located in the latter for operating the said 95 member, and means within the cap for illuminating the member and cylinder.

6. A barber-pole having a rotatable illuminated member with a spindle extending therethrough and forming a movable support therefor, and a stationary transparent cylinder surrounding the said member. 100

7. A barber-pole having an inner rotatable member having a closed bottom and an open top, means for illuminating the latter from 105 the interior and located over said top, and an upper exteriorly-exposed wind-actuated device for operating the said rotatable member.

In testimony that I claim the foregoing as my own I have hereto affixed my signature in 110 the presence of two witnesses,

CHRISTIAN RASMUS HANSON.
